UNITED STATES PATENT OFFICE.

JOHNSTON MEALEY, OF HOWARD LAKE, MINNESOTA, ASSIGNOR OF ONE-HALF TO JOHN F. McDONALD, OF MINNEAPOLIS, MINNESOTA.

OVERDRAW-CHECKREIN FASTENER.

SPECIFICATION forming part of Letters Patent No. 628,277, dated July 4, 1899.

Application filed May 17, 1898. Serial No. 680,919. (No model.)

To all whom it may concern:

Be it known that I, JOHNSTON MEALEY, of Howard Lake, Wright county, State of Minnesota, have invented certain new and useful 5 Improvements in Overdraw-Checkrein Fasteners, of which the following is a specification.

This invention relates to means for fastening bridle-checkreins; and the object of the 10 invention is to provide a check hook or fastener which will securely hold the checkrein and yet permit the easy detachment of the checkrein when desired.

The particular object of the invention is to 15 provide a checkrein holder or fastener which will tend to lift and level the harness-saddle instead of rolling or tipping the same forward when a pull is exerted on the checkrein.

The invention consists in a checkrein-fas- 20 tener of the construction hereinafter de- scribed, and particularly pointed out in the claims.

The invention will be more readily under- 25 stood by reference to the accompanying draw- ings, forming part of this specification, and in which—

Figure 1 is a plan view of a check-fastener embodying my invention. Fig. 2 is a vertical section thereof. Fig. 3 is a perspective 30 view of the same. Fig. 4 is a similar per- spective view showing the end or loop of the checkrein being inserted into the fastening. Fig. 5 is a perspective view showing the check 35 strap or rein in place.

As shown in the drawings, the device com- 40 prises the main block or bar 2, the rear bar 3, and the forward bar 4. The bar 2 has a shank 5, whereby the device is secured upon the harness saddle or pad. The bars 2 and 3 are connected by the side portion or plate 6, and the bar 3 is provided with the head 7, formed by cutting or making the slot 8 in the side plate or portion 9, that connects the bar 2 and the forward bar 4. At the end of the 45 bar 4 is the downwardly-extending lug or finger 10. The slot 8 leads between the bars 2 and 3, and one side of the loop of the rein or strap is inserted through this slot or opening, and the loop is caught on the bar 3. The loop 50 will be held between the enlarged or wide

ends or plates 6 and 7. The straps or sides of the rein are placed together and are passed over the top of the bar 2 and bent in under the bar 4, the end of said bar being separated from the plate 6 by a considerable space to 55 allow the easy insertion of the intermediate parts of the strap. The strap will be held beneath the bar 4 by the depending lug or finger 10 and by the engagement of the op- 60 posite edges with the portion 9 at the oppo- site end of the bar portion 4. The arrange- ment is such that the top of the bar 2 is above a plane including the bottoms of the bars 3 and 4, so that the strap will be crimped or bent over the bar 2, and there will be suffi- 65 cient friction to prevent the pushing back of the loop in such a way as to allow any chance for its becoming free from the bar 3. The bar 4 is preferably arranged at a greater dis- tance than the bar 3 from the bar 2, with the 70 result that the leverage is in favor of the bar 4, and when a pull is exerted upon the strap or rein the tendency will be to lift the bar 4 and with it the forward part of the saddle or pad, thereby preventing the galling of the 75 horse's back.

The device may be used with any kind of harness, is neat in appearance, and cheap in construction.

Having thus described my invention, I 80 claim as new and desire to secure by Letters Patent—

1. A checkrein-fastener, comprising bars 2, 3 and 4, side portions or plates 6 and 9 con- 85 necting said bars, and a shank provided on said bar 2, substantially as described.

2. A checkrein-fastener, comprising bars 2, 3 and 4, connecting side portions or plates 6 and 9, a lug 10 provided on said bar 4 and a shank provided on said bar 2, substantially 90 as described.

3. The checkrein-fastener, comprising the bar or block 2 to be secured upon the harness-saddle, the bar 3 joined to said bar 2 by the plate or side portion 6 and provided with 95 the head 7, and the bar 4 having a lug 10 at its end and joined to said bar 2 by the side plate or portion 9, and the top of said bar 2 being above the bottoms of said bars 3 and 4, substantially as described.

4. The checkrein-fastener, comprising the bars 2, 3 and 4 joined by end parts or plates having alternate openings upon opposite sides between the bars, and said bar 4 being further than the bar 3 from the bar 2, and means securing the fastener upon a harness-saddle, as and for the purpose specified.

In testimony whereof I have hereunto set my hand, this 20th day of April, 1898, at Minneapolis, Minnesota.

JOHNSTON MEALEY.

In presence of—
C. G. HAWLEY,
M. E. GOOLEY.
